UNITED STATES PATENT OFFICE.

MICHAEL E. SOMAN, OF NEW YORK, N. Y., ASSIGNOR TO DAVID KLEBANOFF AND SAMUEL GROSSMAN, COPARTNERS, TRADING AS KLEBANOFF AND GROSSMAN, OF NEW YORK, N. Y.

DESIGN FOR A FINGER RING.

Application filed April 3, 1925. Serial No. 13,002. Term of patent 3½ years.

To all whom it may concern:

Be it known that I, MICHAEL E. SOMAN, a citizen of the United States of America, residing at the city, county, and State of New York, have invented a new, original, and ornamental Design for Finger Rings, of which the following is a specification, reference being had to the accompanying drawings, forming part thereof.

Fig. 1 is a side elevation of a ring bearing the new design;

Fig. 2 is an edge view of the same; and Fig. 3 is a top plan view of the same.

I claim:

The ornamental design for a finger ring as shown.

In witness whereof I have signed this specification this 1st day of April, 1925.

MICHAEL E. SOMAN.
